UNITED STATES PATENT OFFICE

ROBERT L. McINTYRE, OF TORONTO, ONTARIO, CANADA

STRUCTURAL-STEEL JOIST

Application filed October 3, 1928. Serial No. 309,990.

The principal objects of the invention are to improve the construction of exceptionally light structural steel sections being used as joists for the support of floors between the beams in buildings, particularly to provide allowance for variations in measurement between the beams and to provide a substantial means for supporting the ceiling rods close up to the walls and also to provide an adequate support for pipes and wire conduits.

The principal feature of the invention consists in the novel cutting of the ends of the joist beam and the novel construction and arrangement of the stirrup supports for the beam whereby the stirrup supports will sustain the load without flexure though a substantial distance exists between the flange of the main beam and the end of the joist beam, said stirrup having a ribbed cross section.

20 In the drawings, Figure 1 is a perspective view of my improved joist beam structure showing the end supported by one of the main beams of a building.

Figure 2 is a side elevational view of the joist beam showing the main beam in cross section.

Figure 3 is an enlarged cross sectional view through the upper supporting ends of the stirrup.

30 Present-day building construction has adopted the light rolled I-section steel joist and many different forms of devices for supporting the ends of these joists from the main beams of the building, have been devised.

35 In the construction herein shown, the joist 1 is of an ordinary I-section of the required weight for the floor construction. Each end of the joist is cut with an acute angular opening 2 in the web 3.

40 A portion 4 of the web, about three-quarters of an inch in depth, is left extending above the bottom flange 5 thus forming an inverted T-shaped arm at the bottom of the recess.

45 The recess provides a space inside of the wall 6 formed by the fireproofing enclosing the main beam structure 7 and pipes or wire conduits are extended through these recesses and are supported by the rigid T-shaped arms 4.

The joist beam is supported from the flange 8 of the beam 7 by a metal strip 9 which forms a stirrup. The strip 9 fits against the inclined edge 10 of the recess cut in the web of the beam 1 and the sides of said strips 55 are bent inwardly to embrace the flat faces of the web of the beam 1.

The edges of the inwardly turned portions 11 of the stirrup 9 are welded securely to the web of the beam as indicated by the number 12.

The upper end of the stirrup which extends beyond the end of the joist beam 1 is formed with a longitudinal deformation preferably in the form of a rib 13 which effects the very material stiffening of the stirrup member so that in the event of the distance between the inside edges of the main beam flanges 8 varying, the rib portion of the stirrup will present a sufficient support 70 against bending under the load.

The flat portion 9 of the stirrup member extending angularly upward against the inclined edge of the opening cut in the web of the beam 1 engages the top flange of the beam 75 1 and the stirrup and flange are securely united in a weld joint 14.

I have shown the stirrup 9 having its upper end formed with a longitudinal rib 13 to resist the bending stress but it must be understood that I may form this stirrup with any desirable cross-sectional shape in order to properly support the load.

The outer end of the stirrup resting upon the flange 8 of the beam 7 is securely welded 85 in the joint 15 to said flange when the joist has been placed in position.

It will be noted that the top surface of the joist is supported in horizontal alignment with the top surface of the main beam 7 so that the flooring material placed thereon can be carried directly on to the beam 7 from the joist.

What I claim as my invention is:

1. A steel joist construction, comprising the combination with the main building structure and a rolled metal section, of a stirrup member permanently secured to said rolled section and having a single extension to rest 103

upon the main building structure, said extension having a longitudinal deformation.

2. In a structural steel fabrication, a metal beam, and a metal stirrup member permanently secured to the end of the beam in a weld joint and extending outwardly beyond the end of the beam and having a longitudinal rib formed therein to form a rigid extension support.

10 3. A steel joist construction, comprising a beam formed of a rolled metal section, and a stirrup member formed of a length of metal plate bent intermediate of its length to form horizontally and angularly disposed portions, said stirrup having its angularly disposed portion rigidly secured to said rolled section and having its horizontal portion deformed to provide a reinforced extension beyond the end of said rolled metal section for 20 supporting the same on the main building structure.

4. A steel joist construction, comprising a rolled metal beam, a metal stirrup member formed of a strip of plate material bent transversely at a spaced distance from one end thereof to form horizontally and angularly disposed portions, said angularly disposed portions being rigidly connected to the web portion of said beam at the end thereof with 30 said horizontal portion projecting therebeyond and adapted to rest on the main building structure, said horizontal portion being deformed with a longitudinal rib therein extending inwardly from the end thereof and 35 terminating at the transverse bend of said stirrup member.

5. A steel joist construction, comprising a rolled beam section having a triangular portion cut from the end of its web, a stirrup member formed of a strip of plate material bent transversely at a point intermediate of its length to divide said stirrup into horizontal and angularly disposed sections, said angularly disposed section being deformed 45 longitudinally into a U-shaped cross section into which the upwardly and outwardly sloping edge of the cut-out portion of the web extends with the sides of the U-portion overlapping and snugly embracing the web and 50 being permanently fixed to said web, said stirrup being welded at its transverse bend to the top end edge of the beam and having its horizontal portion projecting therebeyond to form a rigid support.

55 6. A steel joist construction, comprising a rolled beam section having a triangular portion cut from the end of its web, a stirrup member formed of a strip of plate metal bent transversely intermediate of its length to 60 form horizontal sloping sections, said sloping sections being placed against the upwardly and outwardly sloping edge of the cut-out portion of the web and having its sides flanged over and intimately embracing the 65 web, said flanged sides being welded along

their edges to the surface of the web of said beam, the end edge of the top flange of said beam being welded to said stirrup at the shoulder formed by said transverse bend, said horizontal portion projecting beyond 70 the end of the top flange of the joist beam to form an extension support therefor.

7. A steel joist construction, comprising a beam formed of a rolled steel section having an acute angular section cut from its web extending inwardly from the ends and leaving a portion of the web extending above the bottom flange, the upper edge thereof being parallel with the flange, a stirrup member formed of a length of steel plate bent transversely at a point inwardly from one end to form a horizontal portion and a sloping portion, said sloping portion being fitted against the upwardly and outwardly sloping edge of the web of the beam and having its sides bent inwardly to snugly embrace the beam and welded along its edge extremities to the web surface of said beam, said stirrup being welded at its junction point between said horizontal and sloping portions to the end of the beam, said horizontal portion projecting beyond the weld at the beam end and being deformed to provide a reinforced extension for the beam to be welded to the main building structure.

8. In a building structure, the combination with the main steel beam, of transverse beams arranged to form joists extending between the main beam, said transverse beams having their webs notched at the ends to form chaces to receive pipes and wires leaving the lower portion of the transverse beams intact to form a support for said pipes and wires, stirrup members rigidly welded to the webs of said transverse beams and to the upper end edge of the top flange thereof and having reinforced extension ends projecting beyond the ends of the joists to rest upon the main beam.
